METHOD OF MINING COAL

Joseph F. Joy, Claremont, N. H., assignor to
Sullivan Machinery Company, Chicago, Ill., a
corporation of Massachusetts

Original application December 2, 1933, Serial No.
700,681. Divided and this application October
7, 1937, Serial No. 167,786

5 Claims. (Cl. 262—1)

This invention relates to an improved mining method, and more particularly to improved methods of mining coal in coal mines.

An object of this invention is to provide improved methods of mining coal wherein the use of explosives is entirely eliminated. Another object is to provide an improved method of mining coal in mines wherein the coal at the coal face is divided up in blocks or cubes and thereafter dislodged from the coal seam wholly without the use of explosives, thereby not only resulting in more safety to the machine operators, but also producing coal in more desirable commercial form. Other objects and advantages of the invention will, however, more fully appear in the course of the following description and as more particularly pointed out in the appended claims.

This application is a division of my copending application Ser. No. 700,681, filed Dec. 2, 1933.

In the accompanying drawings there is shown for purposes of illustration one form which the invention may assume in practice.

In these drawings,—

Fig. 1 is a side elevational view of a coal mining machine of a design particularly adapted to use in performance of the improved mining methods.

Fig. 2 is a plan view of the mining machine shown in Fig. 1.

Fig. 3 is a plan view of a mine chamber or working place showing one method of mining chambers to which the invention is applicable.

Fig. 4 is a vertical cross section through the chamber of Fig. 3, showing a relatively thin coal seam with the machine in place for mining chambers by the improved methods.

Fig. 5 is a plan view of the mine chamber of Fig. 4 as it appears at the conclusion of the improved mining operations.

Fig. 6 is a plan view showing the application of the machine of the invention to the mining of entries by the improved method.

Fig. 7 is a vertical section through the mine entry shown in Fig. 6.

Fig. 8 shows a modification of the method of mining chambers.

In Figs. 1 and 2 of the drawings there is shown a coal mining machine having relatively great flexibility, range and capacity, and having associated therewith dislodging means whereby the improved methods of mining coal may be performed. The mining machine generally comprises a portable base 1 consisting of a wheeled truck adapted to travel along a mine trackway.

Mounted on the truck is a horizontal turntable 2 having in turn mounted thereon an adjustable supporting structure 3 for a kerf cutter 4. The supporting structure 3 comprises an elongated boom 5 pivotally mounted on the forward end of the turntable to swing in a vertical direction with respect thereto and consisting of a rear boom portion 6 and a front boom portion 7, the latter being mounted on the rear boom portion to revolve relative thereto about the longitudinal axis of the boom. Pivotally mounted on the outer extremity of the front boom portion is a cutter head 8 by which the kerf cutter is carried. The cutter head is pivotally mounted on the front boom portion on an axis arranged at right angles to the longitudinal axis of the boom, and the kerf cutter is pivotally mounted on the cutter head to swing relative thereto about an axis at right angles to the pivotal axis of the cutter head. The kerf cutter is of the so-called narrow kerf type and consists of an elongated, relatively thin, plane cutter blade 9 having guided for circulation about its margin an endless cutter chain 10. Propelling mechanism is provided for propelling the machine along the mine trackway at a relatively high transport speed or at a relatively low speed appropriate for cutting. A lock is provided for locking the cutter blade in its different angular positions of adjustment about its pivotal axis with respect to the cutter head. Hydraulically operated means is provided for rotating the turntable, for swinging the boom, rotating the outer boom portion about the boom axis and for tilting the cutter head, comprising a pair of hydraulic turntable rotating cylinders 11, 11, hydraulic boom swinging cylinders 12, hydraulic rotating cylinders 13, 13 for revolving the front boom portion and a hydraulic cylinder 14 for tilting the cutter head relative to the boom. It will thus be seen that the turntable 2 may be rotated relative to the truck, the boom 5 swung vertically about its pivot, the front boom portion 7 revolved relative to the rear boom portion 6, the cutter head 8 tilted relative to the boom and the cutter blade 9 swung about its pivot relative to the cutter head, to enable the adjustment of the kerf cutter into any desired cutting position with respect to the coal face. A hydraulic jack 15 is provided at the axial center of the turntable 5 and engageable with the roof of the mine gallery for anchoring the machine on the trackway during certain of the mining operations. As this mining machine is clearly described in my copending application, Ser. No. 700,681, men-

tioned above, and does not per se enter into this invention, further description and illustration of the detailed structure thereof is considered unnecessary. The dislodging means associated with the coal mining machine, also clearly described in the above mentioned copending application, comprises a breaker pad 16 in the form of an expansible rubber envelope connected through a rigid conduit 17 and a flexible conduit 18 to a connection 19 on the machine so that hydraulic fluid under pressure may be supplied from the hydraulic system of the machine to the breaker pad to expand the latter.

To mine or continue the mining of a mine gallery or entry in its forward direction by the improved block-forming method (Figs. 1 and 6), the mining machine is advanced along the track way by its propelling mechanism at high or low speed until the kerf cutter 4 is adjacent to the end wall of the gallery. To cut the bottom kerf in the end wall of the mine gallery, the kerf cutter is brought into a position approximately coincident with the mine floor by proper adjustment of the supporting structure 3 for the kerf cutter, this being accomplished by lowering the boom 5 by means of the boom swinging cylinders 12, thereby tilting the boom 5 downward and at the same time operating the cutter head tilting cylinder 14, thereby retaining the level of the kerf cutter in a position horizontal with the mine floor while the boom is being lowered. The kerf cutter now rests approximately on the mine floor in a horizontal plane. The turntable 2 is now swung horizontally by the turntable rotating cylinders 11 until the tip of the kerf cutter is in the corner between the side wall and the end wall of the mine gallery. To make the sumping cut, the propelling mechanism of the machine is now set in operation, causing the machine to advance along the trackway in a longitudinal direction; meanwhile the cutter chain is travelling about the margin of the cutter blade, cutting its way into the end wall of the mine gallery in the lower corner thereof. When the usable part of the kerf cutter is buried its full length in the mine wall (Figs. 1 and 6), the forward movement of the machine is halted.

A sumping cut may be made in the side wall by manipulating the turntable swinging cylinders 11 and the head tilting cylinder 14 simultaneously, as shown in the upper right hand corner of Fig. 3. In this way, the kerf cutter is maintained perpendicular to the working face while the turntable 2 is swung to force the kerf cutter to cut its way inward. To complete the bottom kerf, the machine is now anchored by the hydraulic jack 15 against the mine roof, and by admitting pressure fluid to the turntable rotating cylinders 11, the turntable 2 is swung sidewise through an angular path, carrying with it the cutting mechanism which it supports: the cutter chain during this operation cuts a fan-shaped kerf deep in the end of the mine wall (Fig. 3). When the sidewise swinging of the turntable has been completed, so that the tip of the kerf cutter now has reached the position which the gallery wall will have when extended, the rotation of the turntable is halted and the machine released from its anchor with the mine gallery roof. The machine is then propelled backward along the trackway, causing the tip of the kerf cutter to trace a path coincident with the proposed extension of the mine gallery side wall, and thus completing the bottom kerf. The backward motion of the machine is halted when

the tip of the kerf cutter emerges again into the mine gallery, completing the bottom horizontal kerf.

To make the top kerf in the end of the mine gallery parallel to the bottom kerf, the cutter head 8 is now inverted by operating the hydraulic cylinders 13 for revolving the front boom portion 7, thereby rotating the front boom portion and the cutter head and kerf cutter connected to it. The cutter head 8 now occupies the inverted position shown in dotted lines in Fig. 1, but with the kerf cutter extending forward. By admitting pressure fluid to the boom swinging cylinders 12, and simultaneously admitting pressure fluid to the cutter head tilting cylinder 14, the boom 5 is raised and at the same time the kerf cutter maintained parallel to the mine floor. The kerf cutter comes to rest in a position adjacent to the mine roof and approximately parallel to the mine floor. The boom 5 is now swung sidewise exactly as in making the bottom kerf, until the tip of the kerf cutter rests in the upper corner between the ceiling, the end wall and the side wall. The sumping cut is now made as before by advancing the machine along the mine trackway, causing the tip of the kerf cutter to cut its way into the mine end wall until all of the usable length of the kerf cutter has penetrated the coal seam. The machine is now halted and is anchored by the hydraulic jack 15 against the mine gallery ceiling. The sidewise kerf is now completed by admitting pressure fluid to the turntable rotating cylinders 11, causing the kerf cutter to execute an angular kerf exactly similar and parallel to the corresponding bottom kerf, pivoting around the turntable axis. When the fan-shaped top kerf has been completed, and the tip of the kerf cutter coincides with the proposed extension of the mine gallery side wall, the anchor with the mine roof is released and the machine is caused to move backward along the trackway, withdrawing the kerf cutter from the coal seam and completing the top kerf. It is obvious that by a repetition of the operations just described, kerfs may be cut in a horizontal or angular plane at any point intermediate the coal seam between the roof and floor thereof. This makes possible the cutting out of stratified bands of dirt or impurities that may exist in the coal seam and the definite separation of such dirt or impurities from the coal during the mining process.

To make the shearing or vertical kerfs, pressure fluid is admitted to the cutter head rotating cylinders 13, causing them to rotate the front boom portion 7 through a quarter turn until the plane of the kerf cutter is vertical. The turntable 2 is then swung sidewise by admitting pressure fluid to the turntable rotating cylinders 11 and simultaneously to the cutter head tilting cylinder 14 until the bottom of the kerf cutter rests against the side wall of the mine gallery. The boom 5 is then raised until the kerf cutter tip rests in one of the upper corners between the end wall, side wall and ceiling. The sumping cut is now performed as before by advancing the machine along the trackway, the cutter chain cutting its way into the end wall in a vertical sump. When the kerf cutter is buried in the mine wall throughout its usable length, the machine is halted and again anchored by the hydraulic jack 15 in position on the trackway. The turntable 2 remains inoperative, while pressure fluid is admitted to the boom swinging cylinders 12, causing the boom 5 to move downward and making the kerf cut-

ter cut a fan-shaped vertical kerf. When the tip of the kerf cutter reaches the proposed extension of the floor level, the boom swinging is halted, the machine released from its anchor with the 5 roof, and the machine caused to move backward along the trackway, withdrawing the kerf cutter from the mine wall and completing the vertical kerf.

The vertical kerf on the opposite side of the 0 mine gallery is completed in a similar manner, thereby blocking out a large block of coal in the end of the mine gallery. This coal block may be further sub-divided, if necessary, in any desired manner by cutting additional kerfs in the 5 way previously described, as by cutting a plurality of vertical kerfs intermediate of and parallel to the side wall kerfs. The individual blocks may then be detached from their rearward connections with the coal bank by using the expansible 0 breaking device 16 inserted in a kerf. Prior to breaking the block, a coal drag or pan may be placed in the undercut kerf under the block to receive it when it has been detached. Preferably, however, I employ the kerf cutter 4 itself for this 5 purpose, as shown in Fig. 5. The detached block may then be removed by dragging it out on the pan or kerf cutter.

To utilize the machine in long-wall mining, the kerf cutter 4 is swung sidewise angularly until 0 it occupies a position substantially at right angles to the longitudinal axis of the boom 5. This is done by releasing the lock for the cutter blade, the lock being re-applied when the desired position has been reached. The kerf cutter is lowered to the floor level by operating the boom swinging cylinders 12 and the cutter head tilting cylinder 14. The sumping cut is now made into the side wall of the gallery by anchoring the machine by the hydraulic jack 15 against the mine ceiling and swinging the kerf cutter into the side wall of the mine gallery by actuating the turntable rotating cylinders 11. When the sumping cut has been completed, the cutting of the long-wall horizontal kerf may be accomplished 5 by releasing the anchor of the machine and propelling the entire machine longitudinally along the mine trackway. The kerf cutter thereby cuts a kerf at the floor level deep in the side wall of the mine gallery. The long-wall top kerf is cut in precisely the same manner as the bottom kerf, after the kerf cutter has been inverted by the use of the cutter head rotating cylinders in the manner previously described in making the end wall overcut. The vertical or shearing kerfs in the side wall are also made in the same manner as the vertical kerfs in the end wall, namely, by rotating the cutter head 8 through a quarter turn so that the kerf cutter plane is vertical, and then operating the boom swinging cylinders 12 and the kerf cutter tilting cylinder 14.

The improved methods of mining with the coal cutter of the invention differ radically from the conventional methods used with the coal mining machines of the prior art. The ordinary coal mining machine is merely the mechanical substitute for the hand mining by coal picks that was performed earlier in the development of the coal mining industry. Ordinarily these hand or machine "minings" were horizontal kerfs made in the face of the coal seam usually at or near the floor line, but occasionally in the top or at points intermediate of the seam. In addition to these "horizontal minings", "vertical minings" were made in some cases to better facilitate the removal of the coal. The purpose of either hand-

made or machine-made "minings" has hitherto always been that of creating a cavity in the face of the coal seam to permit expansion of coal exposed to the blasting force of explosives used and to relieve the otherwise dangerous pressure acting against and tending to crush the sidewalls and roof of the working place. Due to the high expansibility of explosive gases, their pressure is exerted even after the coal has been dislodged. The degree of relief afforded depends upon the 5 size of the "mining" which after more than fifty years of mining machine operations has become quite generally standardized at the width of six inches. No explosives, however, are used in the improved method of coal extraction, utilizing the present machine, hence no such expansive space is necessary. In contrast, the coal is dislodged by a hydraulic breaker pad 16 inserted in the kerf cut by the mining machine. The instant 10 the coal is dislodged, the dislodging pressure ceases to act, because of the relative inexpandability of the breaker pad liquid. The block-forming and breaker pad system of mining thus introduces a new method. 15

Figs. 3 to 8 inclusive show details of the application of the invention to the block-forming system of mining. This system consists of dividing the face of the seam into relatively large blocks or cubes of coal to be subsequently, by means of the hydraulic breaker pad 16, dislodged and sufficiently fractured for convenient loading. From Fig. 3 it is obvious that to perform the block-forming operations necessary to make this system of mining practical necessitates the use of a machine embodying flexibility and range such as has not heretofore been provided in conventional wide-kerf mining machines. Furthermore, the cuttings or "fines" made by conventional wide-kerf mining machines are of a commercially undesirable size and difficult to dispose of even at 20 prices much below the cost of production. This fact precludes the use of modified conventional wide-kerf mining machines for carrying out the extensive cutting operations necessary for dividing the seam into blocks according to the block-forming system. Furthermore the block-forming system involves the making of kerfs either horizontally or vertically at points longitudinal with or at an angle to the projected course of the working place, hence the function of cutting becomes 25 quite different from that of conventional mining machines. The present coal mining machine, embodying greater flexibility, range and capacity to perform has been invented to meet these special needs which conventional machines cannot satisfy. In the example shown in Fig. 3 a number of 30 positions of the cutter blade are illustrated as well as the application of the hydraulic breaker pad 16 as provided for breaking down the coal. In this case the working face is advanced in steps in order 35 to gain the roof protection afforded by the sidewings or steps of coal. 40

The invention also provides means for cutting kerfs in the roof or floor for the quick and convenient dislodgment thereof through the use of 45 the hydraulic breaker pad by the application of pressure to the kerfs thus formed. An example of this is illustrated in Figure 4, where the floor has been removed to provide head room, as is sometimes required in extremely thin seams of 50 coal. These kerfs are shown (Figure 3) in the floor near the face of the seam.

Figure 5 shows the manner in which the "key block" is withdrawn from the face while resting on the kerf cutter. To perform this operation the 55

kerf cutter is thrust beneath the "key block" while the back end of the latter still remains attached to the coal seam. The block is conveniently dislodged by application of the breaker pad 16 in the top kerf. In some cases, however, the weight and gravitational leverage of the overhanging coal block itself, where the coal parts freely from the roof, makes the top kerf unnecessary, in which case pressure is applied sidewise in 10 the vertical kerfs to dislodge the cut blocks. After the "key block" has been dislodged the machine is propelled away from the face by its tractive effort and in so doing it withdraws the "key block". Figure 5 also shows the dislodged coal as 15 it would appear after the application of pressure coming from the use of the hydraulic breaker pad. Figure 6 shows the application of the invention to a working face by so-called "pillar extraction". This is used where it is desired to carry the track 20 on the side of the working face to permit the subsequent mining of the sidewall adjacent thereto. Figure 8 shows a modified procedure wherein the wing blocks are removed in two following operations. The blocks are removed in the order according to the numbers as given.

In using the apparatus and method in connection with mechanical loading devices, and also as an optional procedure with hand loading, it has been found valuable to form the downwardly-directed diagonal kerf (Figure 1). This kerf is 30 cut by raising the boom 5 and operating the head tilting mechanism. The downwardly-angled kerf approaches the horizontal lower kerf at its backward end within the coal bank. The 35 kerfs thus made serve to outline the upper and lower faces of a wedge-shaped block of coal. The main block of coal above this wedge-shaped block may then be detached from its rearward connection with the coal bank by employing the 40 hydraulic breaker pad 16 deep within the upper horizontal kerf, as previously described. The main block comes to rest on top of the wedge-shaped block, the latter being then removed by the loading machine, excavated by hand, or 45 withdrawn by any convenient means, such as by a coal drag. When this is done, the main block then falls outward from the coal bank onto the floor of the mine chamber, either breaking itself up by its fall or else being easily broken up by hand or in connection with the operation of the 50 mechanical loading machine. This procedure causes the block to fall outward into the mine chamber by its own action.

While there is in this application specifically 55 described one form which the invention may assume in practice, it will be understood that

this form of the same is shown for purposes of illustration and that the invention may be modified and embodied in various other forms without departing from its spirit or the scope of the appended claims.

What I claim as new and desire to secure by Letters Patent, is:

1. A method of mining coal comprising forming a kerf in a mine wall by the swinging movement of a kerf-forming member, retaining the kerf-forming member in said kerf while dislodging the coal, and withdrawing the coal from the mine wall upon said kerf-forming member.

2. A method of mining coal including forming a kerf in a mine wall by the swinging movement of a kerf-forming member, retaining the kerf-forming member in said kerf while dislodging the coal above said kerf, and withdrawing the dislodged coal in blocks from the mine wall upon the kerf-forming member by withdrawing said kerf-forming member from the mine wall.

3. A method of mining coal including forming a plurality of kerfs in a mine wall by a plurality of swinging movements of a kerf-forming member, retaining the kerf-forming member in the lowermost kerf while applying a dislodging force to the coal at a point remote from said kerf-forming member, dislodging said coal in blocks from the mine wall onto said kerf-forming member, and withdrawing the kerf-forming member and the coal block thereon simultaneously from the mine wall.

4. A method of mining coal including forming a plurality of horizontal and vertical kerfs in a mine wall, said vertical kerfs converging toward one another within the mine wall, retaining the kerf-forming member in the lowermost kerf while applying a dislodging force to the coal at a point remote from said kerf-forming member, dislodging said coal in blocks from the mine wall onto said kerf-forming member, and withdrawing said kerf-forming member and the coal block thereon simultaneously from the mine wall.

5. A method of mining coal including forming in a mine wall parallel horizontal kerfs and parallel vertical kerfs to outline the top, bottom and sides of a block of coal attached at its rear side to the mine wall, retaining the kerf-forming member in the bottom horizontal kerf while applying a dislodging force to the coal at the top of the block to dislodge the block from its attachment to the mine wall onto said kerf-forming member, and withdrawing the block intact from the mine wall while supported on said kerf-forming member.

JOSEPH F. JOY.
